Attorney

UNITED STATES PATENT OFFICE

DAVID ALTMAN, OF BALTIMORE, MARYLAND, ASSIGNOR OF FIFTY PER CENT TO MEYER DAVIDSON, OF BALTIMORE, MARYLAND

PAPER BAG

Application filed September 19, 1931. Serial No. 563,689.

This invention relates to paper bags, boxes and containers in general and more particularly to improvements in the construction thereof for facilitating the sealing of the same.

Among the principal objects of the present invention is to provide means in a container, such as a paper bag, for sealing the normally open end thereof, this sealing means being of such character as to eliminate the necessity of tying the filled container with string or the like.

A further object of the invention is the provision of a gummed area centrally located at the top of one of the panels of the container such that when the same is filled and the top ends thereof are folded over in the usual manner, the gummed area may be moistened and permanently secured in place to seal the container.

A still further object of the invention is to provide a standard paper bag with a gummed area centrally located in the top end of one of the panels of the bag, this gummed area being of such character that after it has been secured in place to seal the bag, the latter may be readily opened to remove the contents thereof without destroying or injuring that portion of the bag to which the gummed area was secured.

Other objects and advantages of the invention will be apparent hereinafter.

The invention consists substantially in the combination, construction, location and relative arrangement of parts, all as will appear more fully hereinafter, as shown in the accompanying drawing, and as finally pointed out in the appended claims. In the accompanying drawing, the invention has been shown, for purposes of illustration, as incorporated in a paper bag. It will be understood, of course, that the invention may as readily be incorporated in other containers, such as paper boxes and the like, which are characterized by the provision of an openable flap, and it is not intended therefore to limit the application of the invention solely to the form of container illustrated in the drawing.

In the accompanying drawing:

Figure 1 is a perspective view of an ordinary paper bag embodying the present invention, the bag being shown filled with material and with the top thereof sealed; 85

Figure 2 is a perspective view of the bag shown in Figure 1 as it appears when in flat condition and prior to being filled;

Figures 3 and 4 are views similar to that of Figure 2 showing modified forms of the 60 gummed areas;

Figure 5 is a perspective view of the upper end of a bag showing a still further modified form of gummed area; and

Figure 6 is a perspective view of the top 85 end of a filled bag showing the seal broken preliminarily to removing the contents therefrom.

Referring now to the drawing and more particularly to Figures 1, 2 and 6, it will 70 be observed that the invention has been embodied in a container which in the instance illustrated is in the form of a bag 10 of standard form having back and front panels 11 and 12 and side plaits 13-13, these side 75 plaits being respectively adapted to be folded in order to permit the bag to be collapsed into the substantially flat form shown in Figure 2. In this standard form of bag, the back panel or wall 11 thereof is usually 80 of greater length than and extends above the top edge of the front panel or wall 12.

Provided in the back panel 11 immediately adjacent the top edge thereof is a centrally located area or zone 14 the inner surface of 85 which is gummed. As appears most clearly in Figure 2 this gummed area 14 may be of triangular shape, the area thereof being defined by the perforated lines 15 and 16 and the top edge of the panel 11. In the use of this bag, the latter is first expanded in the usual manner and then filled with the material to be contained therein whereupon the open top or mouth of the bag is folded upon 90 itself as shown most clearly in Figure 1 and in such manner as to leave the gummed area 14 free to be secured to the external surface of the front panel 12 of the bag. It will 95 be understood that this gummed area 14 is 100

readily secured to the panel 12 upon moistening the adhesive material.

In order to open the bag and so permit the removal of the contents therefrom, it is merely necessary to tear open the sealed top flap along the perforated lines 15 and 16. It is important to note that in so breaking the seal the gummed area 14 remains secured to the front panel 12 of the bag (see Figure 6), thereby obviating the likelihood of tearing the panel 12.

In Figure 3 the gummed area 14^a is of circular form, while in Figure 4 the gummed area 14^b is of rectangular form. In both of these modifications the gummed areas are rendered readily separable from the panel or wall 11 of the bag through the provision of perforated lines similar to those provided in the form of bag shown in Figure 2. Instead of providing perforated lines for facilitating the separation of the gummed area of the bag from the remaining portion thereof, scored lines 17 may be provided as shown in Figure 5.

By means of the present invention, the necessity for using twine is eliminated as is the possibility of tearing the bag below the mouth thereof as when an ordinary sealing flap is employed. Perforated or scored lines which circumscribe the gummed areas make it possible to open the top of the bag without rendering the same useless after it has once been opened. It will be understood of course that the invention is susceptible of various changes and modifications from time to time without departing from the real spirit or general principles thereof, and it is accordingly intended to claim the same broadly, as well as specifically, as indicated by the appended claims.

What is claimed as new and useful is:—

1. In a paper bag, in combination, a pair of main walls the vertical edges of which are respectively interconnected by side plaits, a gummed zone provided in the upper portion of one wall of the bag for adhesive securement to the other wall thereof, and means circumscribing said gummed zone for rendering the same bodily separable from the surrounding portion of the wall in which it is provided, the upper edge of said gummed zone being coincident with the upper edge of the wall last mentioned.

2. A paper bag of the character described comprising front and rear walls and interconnecting side plaits, one of said walls being provided adjacent the upper edge thereof with an area the inner surface of which is coated with adhesive material, and means circumscribing said area and terminating in said upper edge for rendering the same bodily separable from the surrounding portion of the wall in which it is provided.

3. A paper bag having front and rear panels and interconnecting side plaits, the

upper portions of said panels and plaits being foldable, when the bag is filled, as to provide one of said panels with a top flap having a free edge overlying the other panel, said flap being provided on the inner surface thereof with a gummed area adapted to be sealed to the underlying panel of the bag, the outer edge of said gummed area being substantially coincident with said free edge of the top flap, and means circumscribing said gummed area terminating in said free edge for rendering the same bodily separable from the surrounding portion of the flap when the latter is separated from said underlying panel.

In testimony whereof, I have hereunto affixed my signature.

DAVID ALTMAN.
